DESIGN FOR A DRESS

Tinna Lauterstein, New York, N. Y.

Application December 28, 1940, Serial No. 97,668

Term of patent 3½ years

To all whom it may concern:

Be it known that I, Tinna Lauterstein, a citizen of the United States, residing in the city and State of New York, county of Kings, have invented a new, original, and ornamental Design for a Dress, of which the following is a specification, reference being had to the accompanying drawing, forming a part thereof.

Fig. 1 is a front view of a dress showing my new design,

Fig. 2 is a rear view thereof.

Fig. 3 is a fragmentary front view of the dress, with the separable collar thereof removed.

The characteristic feature of my design resides in the combination on the specific dress disclosed of the specific lace yoke and collar.

I claim:

The ornamental design for a dress, substantially as shown and described.

TINNA LAUTERSTEIN.
